CLAIM

The ornamental design for an electric support for sofa, as shown and described.

DESCRIPTION

FIG. 1 is a front elevational view of an electric support for sofa showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a first perspective view thereof;

FIG. 8 is a second perspective view thereof shown in an alternate position; and,

(Continued)

FIG. 9 is a second perspective view thereof, shown in an alternate position mounted to unclaimed environment. The broken line portion of the figure drawings is included to show environment that forms no part of the claimed design.

1 Claim, 7 Drawing Sheets
